SET OF PLAYING CARDS

Dorothy W. Smith, 1496 Woodmont Blvd.,
Nashville, Tenn.

Filed May 25, 1960, Ser. No. 60,724

Term of patent 14 years

(Cl. D34—5)

FIG. 1

FIG. 2

FIG. 3

FIG. 4

FIG. 5

FIG. 6

FIG. 7

Figs. 1—5 are face views of the face cards of a set of playing cards showing my new design;

Fig. 6 is a face view of the other cards in the set of playing cards; and

Fig. 7 is a back view of each card in the set.

The dominant features of my design reside in the portions shown in full lines.

I claim:

The ornamental design for a set of playing cards, as shown and described.
